UNITED STATES PATENT OFFICE.

JOHN WHELAN, OF WASHINGTON, DISTRICT OF COLUMBIA, ASSIGNOR OF
ONE-THIRD TO JAMES NOLAN, OF SAME PLACE.

ELECTRICAL CONDUIT.

SPECIFICATION forming part of Letters Patent No. 393,346, dated November 20, 1888.

Application filed July 25, 1888. Serial No. 281,024. (No model.)

To all whom it may concern:

Be it known that I, JOHN WHELAN, of Washington, in the District of Columbia, have invented certain new and useful Improvements 5 in Electrical Conduits; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in 15 underground conduits for electrical cables or conductors.

The object of my invention is to provide an improved conduit which shall be more durable, simple, and cheaper in construction than those heretofore in use, and which shall 20 be always dry and clean, having a thorough draft of air and perfect ventilation through all its parts. Access can also be had to all parts of the conduit by using one or more locking-plates on each block or section, to keep the 25 other plates secure in place.

With these ends in view my invention consists in certain novel features of construction and combinations of parts, more fully described hereinafter, and particularly pointed out in 30 the claims.

Referring to the accompanying drawings, Figure 1 is a perspective view of a portion of the conduit, one side of the same being removed to show the cables in the interior. Fig. 35 2 is a longitudinal vertical section of the conduit. Fig. 3 is an elevation showing the conduit serving the purpose of a curbstone, heavy lines showing where the sides are jointed. Fig. 4 is a perspective view of a section of 40 the conduit, a portion of the cover and side being removed to clearly show the manner of jointing together the parts, the cables and shelves being removed. Fig. 5 is a vertical cross-section of the conduit, showing the venti- 45 lating and drain pipes, also the shelves and cables. Figs. 6, 7, and 8 are detached views of the lock for the locking-plate of the cover. Fig. 9 is a top plan of one of the shelves. Fig. 10 is a vertical section of one of the joints for the 50 sides of the conduit. Fig. 11 is a cross-section

of same on line xx , Fig. 10; and Fig. 12 is a diagram of a street-crossing, showing the manner of laying the conduit at street-crossings.

The conduit, as shown, is preferably rectangular in shape and comprises bottom, side, and top plates, all made to a standard to render the parts interchangeable when broken, or for other reasons. The parts are united and jointed together in an exceedingly simple and cheap manner, dispensing with the use of 55 screws, bolts, and nuts, or the like. The bottom plates, A, of the conduit are made of suitable material and of the desired dimensions, and are provided upon their upper sides, near their longitudinal edges, with parallel 60 grooves aa , into which the lower edges of the side plates, B, snugly fit. The bottom plates are also provided upon their upper faces, near the grooves, with one or more lugs or cleats, b , the edges of which, lying parallel with the 65 grooves a , are undercut or beveled, as shown. The side plates, at their lower inner sides, are provided with corresponding cleats or lugs, c , provided with beveled or longitudinal edges to engage the undercut edges of 70 75 cleats b . Thus it will be readily seen that to fasten the side pieces and bottom together the lower edges of the side plates are inserted in grooves aa with the cleats disengaged. The sides are then slid longitudinally until the bevelled edges of cleats c slide into the dovetailed or undercut portion of cleat b , thus forming a slip or dovetailed joint and securely fastening the parts together. The bottom plates are secured together by two cleats b engag- 80 85 ing one cleat c , and the same can be reversed where the joints between the side plates occur, as shown in Fig. 4. The side plates on the same sides of the conduit are jointed together, as shown in Figs. 10 and 11, preferably by 90 means of a slip-tongue joint, the adjoining vertical edges being grooved and the tongue a' inserted. On level ground of course the edges of the side plates will be vertical, (see joint on left-hand side of Fig. 3,) but where 95 the conduit is ascending or descending a grade the edges of the side plates will be diagonal or inclined. (See joint on right-hand side of Fig. 3.)

The top plates or covers, C, of the conduit are 100

provided with grooves d and undercut or beveled cleats d' to engage the top edges of side plates, B, and beveled cleats e at the top inner sides of plates B, forming slip or beveled joints similar to those by which the bottom plates are secured to the side plates.

In order to allow the covers to be removed at will by allowing them the necessary longitudinal movement to disengage the cleats at 10 certain suitable intervals along the conduit, locking plates or covers are located, which are not secured to the side pieces by the slip-joints, but are provided with locks which secure them to the sides, and which, when unlocked, allow the locking-plates to be lifted directly from the conduit and thus leave sufficient space for the longitudinal movement necessary for removing the other sections of the cover. The lock for said locking-plates 20 consists of a cam, D, mounted on the under side of said plates to turn horizontally and provided with diametrically-opposite lugs or projections f to fit into grooves or sockets f' in the inner sides of the side plates when the cover is locked. The cam is provided with a hub, d^3 , turning in a socket or bearing in the cover-plate, (see Fig. 6,) and said hub and cam are provided with a central angular or elongated aperture, d^3 , registering with a similar 25 opening through the cover-plate, Fig. 6. It will thus be seen that the lock can be closed or opened by inserting a suitable instrument through said opening and turning the cam in the desired direction. The cam is guided and 30 limited in its movement by pins secured to the cover and extending through slots in the cam, as shown in Fig. 8.

F indicates one or more horizontal shelves for supporting the cables or wires. These shelves 40 are removably supported by and loosely rest upon the lugs or projections F', cast integral with the inner faces of the side plates. The longitudinal edges of said shelves are beveled downwardly and inwardly, as shown, to facilitate their removal by being lifted out from the top and to prevent them from wedging. Upon their upper sides the horizontal bottoms or shelves are provided with diagonal grooves, as shown, having vertical perforations through 45 their bottoms. This is to allow for the circulation of the air and for the escape of moisture to the bottom of the conduit, from which it passes off through drain-pipes L. The bottom of the conduit is left clear and unobstructed 50 to form a drain or water-course to receive all the water and moisture in the conduit and allow it to flow out through pipes L. The conduit can be provided with any desirable number of horizontal shelves or boards, and the 55 cables or wires are separated by sheets of lead or other insulating material. A very desirable material in which to pack the cables is bog mold or peat, (see Fig. 5,) as it is a perfect non-conductor and is indestructible, and once packed will last as long as the conduit itself. It never gets hard, but packs like sawdust, and is always porous and allows ventilation.

The conduit at suitable intervals is provided with induction-pipes N, through which air is forced into the lower portion of the conduit. 70

m indicates eduction-pipes at the upper part of the conduit, through which the air is discharged from the conduit. It will be readily seen that the air entering at the lower portion of the conduit passes up through the cables, 75 keeping the parts thoroughly ventilated and preventing decay. The series of top and bottom plates are united and jointed together, as shown, by lap-joints, by having the meeting-end edges beveled or notched to make a close 80 tight joint between the adjoining edges. The joints, particularly the slip-tongue joints, are preferably firmly seated with heated pitch or asphalt to keep out moisture and lock the plates together.

Where the device is used as a conduit for electric-light cables, sections formed of terra-cotta, lead, or other non-conducting material can be introduced where the conduit passes in proximity to water, gas, or other metallic pipes 90 to prevent the heavy current conveyed over such wires from entering houses or passing into pipes and displacing cocks or valves. Although mention is made of substances of which the conduit might be constructed, I do 95 not wish to limit myself to any particular substance. The floors or shelves which support the cables can be constructed of any suitable material. If desirable, they might be formed of heavy cheap glass, terra-cotta, or creosoted 100 wood.

It is evident that the conduit described can be used as a curb, or on a level with the surface, or buried beneath the surface of the ground.

T indicates a transverse step-piece connected to the top and sides of the conduit by suitable joints and a tongue and groove, as seen in Fig. 3, and is intended to be used at street-crossings or the like where there is an 110 abrupt fall in the surface of the ground.

In the diagram shown in Fig. 12, P indicates the sewer-traps at a street-crossing, and R indicates the conduit. It will be seen that the conduit extends around to the rear of the 115 sewer-traps and crosses the side street a distance from the street upon which the conduit is laid. It should be observed that the angles and turns in the conduit are of the same degree; hence one set of patterns will answer 120 any angle of street, and the sewer-traps or curbs need not be disturbed on account of the conduit. All the similar parts and plates of the conduit are made interchangeable and are duplicates of each other, so that they all fit 125 where put together.

It is clearly evident that various slight changes might be made in the form and arrangement of the parts described without departing from the spirit and scope of my invention; hence I do not wish to limit myself 130 to the precise construction herein set forth.

What I claim is—

1. In an electrical conduit, the combination

of bottom, side, and top or cover plates, with slip or dovetailed joints removably securing the same together, substantially as described.

2. An electrical conduit formed of interchangeable plates removably jointed together to form the top, sides, and bottom of the conduit, substantially as described.

3. In an underground conduit, the combination, with the bottom and sides of the conduit, of the removable cover for the same, comprising plates secured to the sides by slip-joints, and locking-plates capable of being lifted directly from the conduit when unlocked, as set forth.

4. In an underground conduit, the combination, with the sides of the conduit, of a cover and a lock to removably secure the cover upon the conduit, comprising a movable cam upon the under surface of the cover provided with curved transverse slots and having projecting lugs to engage the sides and hold the cover, a hub upon its upper side located in the cover and forming the axis upon which the cam turns, and pins extending from the cover through and confined in the slots in the cam to guide the same in its movement and movably hold it to the cover, said cover, hub, and cam having registering openings for the insertion of a key to operate the lock, substantially as described.

5. In an electrical conduit, the combination, with the sides and top, of the bottom plates jointed together and having longitudinal grooves in which the sides fit and slip, or dovetailed joints securing the bottom plates to the sides, substantially as described.

6. In an electrical conduit, the combination of horizontal shelves to receive the cables located a suitable distance apart and provided with transverse apertures, the lowest shelf be-

ing located a suitable distance from the bottom of the conduit to form a chamber for the collection of water, moisture, &c., drain-pipes extending from the bottom of said chamber, and air induction and eduction pipes opening into, respectively, the lower and upper portion of the conduit, substantially as described.

7. The combination, with the top and bottom plates, of the sides formed by interchangeable plates secured together by slip-tongue joints, said sides and top and bottom plates being secured together by slip-joints, as set forth.

8. The combination, in an electrical conduit, of the shelves having downwardly and inwardly beveled edges, the projections supporting said shelves, the cables, and insulating packing, substantially as described.

9. In an electrical conduit, the combination, with the sides, of the horizontal shelves having downwardly and inwardly beveled edges and diagonal grooves and transverse openings, as set forth.

10. In an underground conduit, a bottom having suitable grooves and beveled cleats arranged at intervals throughout its length, sides fitting in said grooves and secured together by tongue-joints and having cleats to engage said cleats of the bottom and form slip-joints, and a top provided with lap-joints and secured to the sides by slip-joints, in combination with a transverse step-piece for use at crossings, substantially as described.

In testimony that I claim the foregoing as my own I affix my signature in presence of two witnesses.

JOHN WHELAN.
